UNITED STATES PATENT OFFICE.

RICHARD HELLMANN, OF LONG ISLAND CITY, NEW YORK.

DRYING APPARATUS.

Application filed March 18, 1924. Serial No. 699,969.

To all whom it may concern:

Be it known that I, RICHARD HELLMANN, a citizen of the United States, and a resident of Long Island City, county of Queens, 5 and State of New York, have invented certain new and useful Improvements in Drying Apparatus, of which the following is a specification.

This invention relates to drying apparatus 10 and more particularly to means for rapidly and thoroughly drying bottles or jars upon their discharge from an automatic washing machine.

In the washing and sterilization of glass 15 bottles or jars in which any edible commodities are contained, as for instance, mayonnaise dressing, the bottles are arranged in an inverted position in trays, such trays being carried and discharged from the washing 20 chamber by a suitable conveyor. The surfaces of the bottles are covered with water, and it is essential that this water shall be thoroughly evaporated and the glass surfaces of the bottles thoroughly dried before 25 the bottles are passed to the filling machines. The bottles are arranged in the trays in inverted position, and have concave bottom surfaces. Upon these concave surfaces water collects in considerable quantity 30 and heretofore it has been a difficult matter to insure the complete evaporation of this relatively large quantity of water, so that when the bottles leave the drying chamber, the bottom surfaces thereof would be entirely 35 free of water and thoroughly dry.

It is a prominent object of my present improvements to provide a suitable and effective means for discharging the greater part of this water collecting upon the concave surfaces of the bottles, so that only 40 a small quantity remains to be evaporated by the hot air in the passage of the bottle-carrying tray through the drying chamber.

At the open end of the bottle, the same is 45 provided with an exteriorly threaded neck to receive a metal cap and it has heretofore also been a difficult matter to entirely free the threads on this neck portion of the bottle from the globules of water collecting thereon. My present invention provides a 50 very effective means for accomplishing this result.

A further object of the invention resides in the provision of improved means for baffling 55 the heat from a series of burners as it rises into the drying chamber and for main-

taining a more effective circulation of the hot air and delivering the air under pressure from the drying chamber in two 60 reversely directed streams upon the bottles as the same enter and leave the said chamber.

With the above and other objects in view, the invention consists in the improved drying apparatus and in the form, construction and relative arrangement of its several parts 65 as will be hereinafter more fully described and illustrated in the accompanying drawings and subsequently incorporated in the subjoined claims.

In the drawings wherein I have illustrated one simple and practical embodiment of my invention and in which similar reference characters designate corresponding parts throughout the several views, Figure 1 is a side elevation of a drying apparatus 70 illustrating a preferred construction thereof. Figure 2 is a top plan view. Figure 3 is a longitudinal section taken on the line 3-3 of Figure 4 and Figure 4 is a transverse section taken on the line 4-4 of Figure 3. 75

Referring in detail to the drawings, for purposes of illustration I have shown the walls of the drying chamber 5, suitably mounted and secured upon the upper ends of the vertical frame standards 6. The drying chamber includes a top wall 7 and the side walls 8, said chamber being open at its bottom and at the opposite ends thereof. 80

Upon the opposite sides of the supporting frame longitudinally extending angle 85 bars 9 are suitably mounted, said bars having inwardly extending horizontal flanges, as clearly shown in Figure 4 of the drawings. Above these angle bars longitudinally extending guide bars 10 are fixed to the upper ends of the vertical supports 11, which are secured to the vertical flanges of the angle bars 9. The purpose of these guide bars 10 will clearly appear from the 90 following description:

At the exit end of the drying chamber 5 a transversely positioned shaft 12 is journaled in the frame structure, said shaft carrying suitable sprockets over which the conveyor chains 13 are engaged. It will be noted that the angle bars 9 are positioned some distance above the lower edges of the side walls 8 of the drying chamber and over the horizontally disposed flanges of these bars, the upper stretches of the respective conveyor chains 13 move. These chains are the familiar link type, certain 100

of the links being provided with suitable flights 13'. These conveyor chains are trained over the idler sprockets 14 mounted upon a second transverse shaft journaled 5 in the lower portion of the frame structure, the lower stretches of the chains extending over and being supported by spaced rods indicated at 15. These conveyor chains also extend through the chamber of the 10 washing machine (not shown) and move in the direction indicated by the arrows in Figure 3 of the drawing.

On one end of the shaft 12 a second sprocket is secured, whereby said shaft is 15 connected by the driving chain 16 with a similar sprocket fixed upon the power shaft 17. This shaft may be operated by a motor or from any other convenient source of power.

20 Additional spaced transverse shafts 18 are mounted in the supporting frame, the said shafts being connected with each other at one of their ends by means of the power transmitting chains 19 whereby the rotation 25 of the several shafts 18 in the same direction is obtained. Upon one or more of these shafts 18 spaced arms 20 are fixed at one of their ends, the other ends of said arms carrying the loosely mounted rollers 21.

Below the plane of the angle bars 9 a plurality of baffle plates 22 are suitably mounted upon the transversely extending bars 23 secured to the frame structure, said 35 baffle plates being spaced from each other longitudinally of the drying chamber. Below each of these baffle plates one or more gas burners 24 of any suitable type are arranged, said burners being connected with 40 a common gas supply pipe 25. The gas flames from the several burners contact with the under sides of the baffle plates 22 so that the hot air drawn upwardly by the flames is diverted by the baffle plates and 45 distributed more or less uniformly, so that there will be a substantially equal temperature throughout the length of the drying chamber.

To the opposite ends of the top wall 50 7 of the drying chamber the pendant or hanging strips of fabric 26 are attached, said fabric strips or curtains presenting a yieldable barrier at the ends of the chamber so that hot air will be retained therein.

55 At the entrance end to the drying chamber there is suitably arranged, below the guides 9, a water receiving and discharging trough 27. At the opposite or exit end of said drying chamber a plurality of spaced 60 tray receiving rollers 28 are suitably mounted. The outlet end of a flat elongated nozzle 29 projects upwardly between adjacent rollers 28 and extends substantially the full length of said rollers, as illustrated 65 in Figures 2 and 4 of the drawings.

Through this nozzle hot air is upwardly discharged under pressure by means of a blower 30, driven by the electric motor 31, the blower chamber being connected by the pipe or conduit 32 with the drying chamber 5 adjacent its exit end. A second blower 33 is mounted upon the top of the drying chamber at the entrance end thereof, the said blower being driven by a second motor 34 and having its intake connected by the pipe 35 with the drying chamber through the top wall thereof at a point substantially midway between the ends of said chamber. The outlet or discharge pipe 36 from the blower 33 delivers the blast 80 of hot air downwardly in front of the entrance to the drying chamber, as indicated in Figure 1 of the drawings.

The glass bottles or jars, indicated as B, are arranged in inverted position in slat bottom trays T, so that air may freely enter between the bottom slats of the tray through the open ends of the bottles to the interior thereof. The bottom walls of the glass bottles B have concave exterior surfaces, as indicated in Figure 3 of the drawings. These trays filled with the bottles are engaged by the flights 13' of the conveyor chains 13 and carried thereby, first through the chamber of the washing machine, where the bottles are thoroughly washed or cleaned by hot water. After leaving the washing chamber, the trays enter one end of the drying chamber, the hanging fabric curtain 26 freely moving inwardly. As the trays 100 enter said chamber, the rollers 21, carried by the arms 20 fixed on the rotating shaft 18, engage the bottom of the tray, and vertically lift or tilt the same upon the conveyor chains 13. Owing to this vertical tilt 105 of the bottles contained in the trays, the greater quantity of the water which has collected upon the concave bottom surfaces of the bottles is caused to drain therefrom, such water dripping through the bottom of 110 the tray into the discharge trough 27. The speed of travel of the conveyor chains and the speed of rotation of the shafts 18 is in such ratio that the rollers 21 will move beyond the end of the tray before the latter 115 has been lifted beyond a predetermined height. As the movement of these rollers continues, the end wall of the tray rides upon said rollers as the lifted end of the tray drops downwardly by gravity to its former position upon the conveyor chains. In the illustrated embodiment of my invention after the tray has thus been lifted by 120 the arms 20 on the shaft 18 at the entrance end of the chamber, as the tray passes onward through said chamber, it is again lifted by a second pair of arms 20 secured on shaft 18. It will also be seen that before 125 the trays are wholly within the chamber 18 they are vertically lifted or tilted. At the 130

same time, a blast of hot air is delivered downwardly through the pipe 36 upon the bottles contained in the tray, so that this air will impinge upon the cylindrical surfaces of the bottles and evaporate the greater part of the water contained thereon. In the continued travel of the bottles through the drying chamber, they are subjected to the action of a very high temperature, so that any water remaining on the concave bottom surfaces of the bottles will be evaporated.

10 The trays with the bottles contained therein are finally discharged from the drying chamber upon the rollers 28, which are arranged at a downward inclination so that the trays will continue their movement by gravity upon these rollers. At this point, as the bottles contained in the trays pass 20 over the nozzle 29, a blast of hot air is delivered through said nozzle upwardly upon the lower ends of the bottles and also within said bottles. Thus any water on the inner surfaces of the bottles will be evaporated and likewise globules of water which have collected on the exterior threads of the bottle neck and which may not have been evaporated in the passage of the bottles through the drying chamber will be entirely 30 evaporated by this upwardly discharged hot air current.

From the foregoing description it will be apparent that I have devised an apparatus whereby the quick and thorough drying of all surfaces of the bottles, without interruption of their continued movement after leaving the washing chamber will be assured. It is of primary importance in the vending of many commodities, that no 40 water shall become incorporated with the material when the bottles or jars are filled. This is particularly true of mayonnaise dressing. However, it is clear that my present improvements might be advantageously 45 utilized for the purpose of drying bottles or containers of other forms, shapes or sizes and designed for the vending of other commodities and food materials. It is also to be understood that any desired number of 50 tray-tilting devices might be utilized and that the drying chamber through which the trays pass may be of other proportions than those indicated in the drawings. Further, the apparatus as herein described is susceptible 55 of embodiment in various other alternative structures and accordingly the privilege is reserved of resorting to all such legitimate changes in the form and relative arrangement of the several parts as may be embodied within the spirit and scope of 60 the appended claims.

I claim:

1. In a drying apparatus, a drying chamber, a conveyor for moving bottle-carrying trays through said chamber, and means for

vertically elevating the trays and tilting them upward on the said conveyor during their passage through the drying chamber to allow fluid on top ends of the bottles carried by the trays to drain therefrom.

70

2. In a drying apparatus, a drying chamber, a conveyor for moving bottle-carrying trays through said chamber, means for vertically elevating the trays and tilting them upward on said conveyor during their passage through the drying chamber and means for directing a blast of hot air upon the bottles while the trays are in a tilted position upon the conveyor.

75

3. In a drying apparatus, a drying chamber, a conveyor for moving bottle-carrying trays through said chamber, means for vertically tilting the trays while they are upon the conveyor, means for directing a blast of hot air downwardly upon the bottles at the entrance to the drying chamber, and additional means for directing a blast of hot air upwardly upon the bottles at the egress end of said chamber.

80

4. In a drying apparatus, a drying chamber, and means for supplying hot air to said chamber, a conveyor for moving bottle-carrying trays through said chamber, a blower connected to the chamber to withdraw hot air therefrom and direct the same, under pressure, downwardly upon the bottles at their entrance to the drying chamber, and an additional blower connected to said chamber to direct a blast of hot air upwardly upon the bottles at the egress end of said chamber.

90

5. In a drying apparatus, a drying chamber, and means for supplying hot air to said chamber, a conveyor for moving bottle-carrying trays through said chamber, a blower connected to the chamber to withdraw hot air therefrom and direct the same, under pressure, downwardly upon the bottles at their entrance to the drying chamber, and means for vertically tilting the trays during their movement through the drying chamber.

105

6. In a drying apparatus, a drying chamber, and means for supplying hot air to said chamber, a conveyor for moving bottle-carrying trays through said chamber, a blower connected to the chamber to withdraw hot air therefrom and direct the same, under pressure, downwardly upon the bottles at their entrance to the drying chamber, and spaced continuously operating devices to engage each tray and vertically tilt the same on the conveyor a plurality of times in the movement of the tray through said chamber.

115

7. In a drying apparatus, a drying chamber, a conveyor for moving slat-bottom trays, having bottles arranged therein in inverted position through said chamber, means for vertically tilting the trays upon the con-

125

130

veyor at the entrance to said chamber to discharge excess water from the bottom surfaces of the bottles, a plurality of burners arranged below the conveyor, and a series of spaced baffles for baffling the hot air from said burners and directing the same upwardly through the bottom of the trays into contact with the bottles.

8. In a drying apparatus, a drying chamber, a conveyor for moving slat-bottom trays, having bottles arranged therein in inverted position through said chamber, means for vertically tilting the trays upon the conveyor at the entrance to said chamber to

discharge excess water from the bottom surfaces of the bottles, a blower connected to said chamber to withdraw hot air therefrom and direct the same downwardly upon the bottles at the entrance to said chamber and an additional blower connected to said chamber to direct a blast of hot air upwardly through the trays and upon the bottles at the egress end of said chamber. 15

In testimony that he claims the foregoing as his invention, and has signed his name 20
hereto. 25

RICHARD HELLMANN.
